UNITED STATES PATENT OFFICE.

TATSUICHIRO ISONO, OF TOKYO, JAPAN, ASSIGNOR TO GENERAL ELECTRIC COMPANY,
A CORPORATION OF NEW YORK.

TRANSFORMER.

Application filed April 10, 1919, Serial No. 289,027, and in Japan April 12, 1918.

My present invention relates to a device for changing or transforming electric voltages, and more particularly to a vacuum tube device for accomplishing the desired purpose.

The object of my invention is to produce a simple and efficient device for transforming voltages, and particularly to secure a secondary voltage of lower value than the primary voltage applied to the device.

The novel features which I believe to be characteristic of my invention are pointed out with particularity in the appended claims. The invention itself, however, both as to its organization and method of operation, together with further objects and advantages thereof will best be understood by reference to the following description taken in connection with the accompanying drawing in which Fig. 1 is a diagrammatic representation of a device constructed in accordance with my invention; Fig. 2 shows the wave form of the primary voltage and secondary current set up in the device; Fig. 3 is a diagrammatic representation of a modification in which two similar devices are used in parallel to obtain a transformation of voltage waves of opposite polarity; Fig. 4 shows the wave form of the primary and secondary currents in the arrangement shown in Fig. 3; and Fig. 5 shows a further modification of my invention.

It has been common practice in the past to use transformers in connection with alternating current voltage measuring instruments, watt meters, frequency meters, etc., for changing the primary voltage into a lower voltage having the same wave form. In cases where transformers are used with very high voltages they have become very bulky and their construction in practice has been limited by reason of insulation difficulties. A more specific object of the present invention is to overcome these disadvantages. It is well known that if two electrodes are inserted within a vacuum tube such as that indicated as 1 in Fig. 1 and one of the electrodes 2 is made in the form of a lamp filament and is heated by means of a battery 3, while the other is made as a conducting plate 4, electric current will flow between the two electrodes only in one direction.

In the case of the present invention this characteristic of such a device is utilized.

In addition to the electrodes 2 and 4, I provide two other electrodes 5 and 6. These two electrodes are connected to opposite terminals of the source of high voltage which it is desired to measure. In the present case the source is indicated as the secondary of transformer 7. It will be noted that the electrodes 2 and 4 are located between the electrodes 5 and 6. A battery 9 is also connected in circuit between the cathode 2 and the cooperating anode 4, the positive terminal of the battery being connected to the anode 4 and the negative terminal to the cathode 2. The current flowing between the cathode 2 and anode 4 depends upon the voltage between electrodes 5 and 6 as well as upon the voltage of the battery 9. Hence if the voltage between the electrodes 5 and 6 is an alternating voltage the current between electrodes 2 and 4 increases when the electrode 5 becomes negative and the electrode 6 becomes positive and decreases when the electrode 5 becomes positive and the electrode 6 becomes negative by reason of the electrostatic fields produced in the neighborhood of the electrodes 5 and 6. In other words, current flowing from the battery 9 is proportional to the voltage between the electrodes 5 and 6. The current which flows between electrodes 2 and 4 will have a component of the form indicated at I in Fig. 2, which corresponds to the half wave form of the voltage wave V when the electrode 6 is positive. The effect will be the same as if a voltage, much smaller than but directly proportional to that between electrodes 5 and 6, were applied between cathode 2 and anode 4. The electrodes 5 and 6 are not necessarily located within the vacuum tube but may be outside of the tube as indicated in Fig. 5, and if desired, may be electrically connected to one of the electrodes 2 or 4 as indicated by dotted lines 12 or 13.

In order to obtain a current in which both half waves of the primary voltage can be reproduced two devices similar to that shown in Fig. 1 may be connected in parallel in the manner indicated in Fig. 3. In this case the source of voltage V is connected to the two devices in such a way that when the electrode nearest the filament of one device is positive, the electrode nearest the filament of the other device is negative and vice versa. Separate batteries of the proper polarity 10 and 11, are provided in this case

for the two devices and the current flowing through the two devices may be measured by means of a meter M which is connected in series with both of the devices. The 5 wave form of the alternating current flowing through this meter M is indicated in Fig. 4 by the curve I_2 . This current corresponds in wave form to the voltage wave V and is directly proportional to the voltage. This current corresponds to the current which is obtained from the secondary 10 of the ordinary transformer which is used in similar cases.

What I claim as new and desire to secure 15 by Letters Patent of the United States, is—

1. A voltage transforming device comprising an evacuated receptacle containing two electrodes to which the voltage to be transformed may be applied, a cathode 20 adapted to emit electrons and a cooperating anode located between said two electrodes, a source of direct current connected to said cathode and anode, and a measuring in-

strument connected in series with said source of direct current. 25

2. A voltage transforming device comprising two evacuated receptacles, each of which contains two electrodes to which the voltage to be transformed may be applied, and a cathode adapted to emit electrons and 30 a cooperating anode located between said two electrodes, sources of direct current connected between cathode and anode of each receptacle, a measuring instrument in series with both of said sources of current, and circuit connections for applying the voltage to be transformed to said first named electrodes in such a way that when the electrode nearest the cathode of one receptacle is positive the electrode nearest the cathode of the other 35 receptacle is negative. 40

In witness whereof, I have hereunto set my hand this seventeenth day of March, 1919

TATSUICHIRO ISONO.
